CLAIM

The ornamental design for a “toilet-to-urinal adapter for potty-training children” as shown and described.

DESCRIPTION

FIG. 1 is a perspective view of the toilet-to-urinal adapter for potty-training children;

FIG. 2 is a backside view thereof;

FIG. 3 is a front view thereof;

FIG. 4 is a left side view thereof;

FIG. 5 is a top view thereof; and,

FIG. 6 is an environmental view thereof.

Broken lines of FIGS. 1-2 illustrate unclaimed features of the toilet-to-urinal adapter. Broken lines of FIG. 7 illustrate environmental features and form no part of the claimed design.
